UNITED STATES PATENT OFFICE.

WILLIAM LODER PARK, OF WINDHAM TOWNSHIP, NORFOLK COUNTY,
CANADA.

WAGON-TONGUE SUPPORT.

SPECIFICATION forming part of Letters Patent No. 743,185, dated November 3, 1903.

Application filed April 11, 1903. Serial No. 152,257. (No model.)

To all whom it may concern:

Be it known that I, WILLIAM LODER PARK, yeoman, in the township of Windham, in the county of Norfolk, in the Province of Ontario, 5 in the Dominion of Canada, (whose post-office address is Simcoe,) have invented a new and useful Improvement in Wagon-Tongue Supports; and I do hereby declare that the following is a clear and exact description of the 10 same.

My invention relates to spring-supports for wagon-tongues; and the objects of my invention are, first, to provide a spring-support for either light or heavy wagons such that it shall 15 remove the weight of the tongue from the horse's neck; second, to afford facilities for holding said tongue in any position from its lowest or ground rest to the perpendicular; third, to provide a simple, durable, and cheap 20 support manufactured from iron and steel and so constructed that it can be attached and detached from a wagon in less than one minute of time without interfering in any manner with the working of the wagon. I attain 25 these objects by the mechanism illustrated in the accompanying drawings, of which the following is an explanation of the same.

Figure 1 is a side view of the device, together with such parts of the old construction 30 as are necessary to show its connections. Fig. 2 shows the independent combination of the several parts of the support. Fig. 3 shows flat view of clasp-hook and side view also, and Fig. 4 the wrench draw-bolt.

35 Referring to the drawings, in Fig. 1 letter K represents the thin side on edge of reach, around which the staple D passes to form an eye at end to receive flat hook C if not used or attached to king-bolt I.

40 D is a staple attached to reach with two bolts, one in front of king-bolt, the other behind it, forming a solid staple for flat hook C.

C represents the flat hook to connect with staple D or king-bolt I to link E. Link E connects flat hook C with staple B in spring 45 at one end, while chain F connects with staple B, passing through spring opposite the one connecting with link E. Chain F then connects with clasp-hook A, passing over wrench draw-bolt H. Next comes wrench draw-bolt 50 H, that holds doubletrees or evener, over which the chain passes to clasp-hook A. Then clasp - hook A is attached to tongue I four inches in front of evener, with two bolts passing through clasp-hook A and tongue I from 55 top side, making the attachment complete.

The clasp-hook A is formed with a key-slot opening, wherein the chain may be adjusted, as desired, to hold the tongue at any proper elevation. 60

The wrench draw-bolt H, over which the chain passes, forms an incline sufficient to hold tongue I at any angle from perpendicular to its lowest or ground rest. The wrench-head of the draw-bolt forms a notch to hold 65 the chain in a central position.

I am aware that prior to my invention several of the parts used in the connection thereof were in public use, and therefore I do not claim those as my invention; but 70

What I desire to secure by Letters Patent is—

The combination in a tongue-support of a flat hook C, clevis D, chain F, wrench draw-bolt H and clasp-hook A, all substantially as 75 described.

In testimony whereof I have signed my name to this specification in the presence of two subscribing witnesses.

WILLIAM LODER PARK.
